Des. 211,616
Patented July 2, 1968

211,616

DISPLAY STAND FOR CANDY OR THE LIKE

William S. Leath, Birmingham, Ala., assignor to EBSCO
Industries, Inc., a corporation of Delaware

Filed Apr. 24, 1967, Ser. No. 6,811

Term of patent 3½ years

(Cl. D80—9)

Fig. 6

Fig. 1

Fig. 2

Fig. 3

Fig.4

Fig.5

FIG. 1 is a perspective view of a display stand for candy or the like showing my new design;

FIG. 2 is a side elevational view thereof;

FIG. 3 is a front elevational view thereof;

FIG. 4 is a top plan view thereof;

FIG. 5 is a rear elevational view thereof; and,

FIG. 6 is a fragmental perspective view of a modified form of the display stand for candy or the like shown in FIG. 1, the omitted portion of the stand having the same appearance as the stand shown in FIGS. 1 through 5.

I claim:

The ornamental design for a display stand for candy or the like, as shown and described.
